Max C. Christensen, Royal Oak, Mich., assignor to Ford
Motor Company, Dearborn, Mich., a corporation of
Delaware

Filed Jan. 4, 1960, Ser. No. 58,901

Term of patent 7 years

(Cl. D35—2)

FIG. 2

FIG. 3

FIGURE 1 is a top plan view of a fertilizer hopper lid embodying my new design.

FIGURE 2 is a side elevational view thereof.

FIGURE 3 is an enlarged end elevational view thereof.

FIGURE 4 is a perspective view thereof, looking from above the lid.

The bottom of the fertilizer hopper lid is substantially similar to the top, but intaglio in form.

I claim:
The ornamental design for a fertilizer hopper lid, as shown and described.
